UNITED STATES PATENT OFFICE.

HUGH DANIEL McCARTY, OF PROVIDENCE, RHODE ISLAND.

DESIGN FOR A BICYCLE-CROWN.

SPECIFICATION forming part of Design No. 27,038, dated May 11, 1897.

Application filed September 23, 1896. Serial No. 606,792. Term of patent 14 years.

To all whom it may concern:

Be it known that I, HUGH DANIEL McCARTY, of Providence, in the county of Providence and State of Rhode Island, have invented and produced a new and original Design for a Bicycle-Crown, of which the following is a full, clear, and exact specification.

Reference is to be had to the accompanying drawings, forming a part of this specification, in which similar characters of reference indicate corresponding parts in both figures.

Figure 1 is a perspective view of a bicycle-crown embodying my design, and Fig. 2 is a front elevation of the same.

The leading feature of my design consists in the plates A B, each having the elliptical end openings E E' and the central round openings E², and the elliptical end bosses C C'

and round central boss D, connecting the said plates. The bosses are tubular, have an unbroken outer surface, and are arranged between the plates with their openings coincident with the openings of the said plates and the end bosses C C' inclined upwardly and inwardly toward the boss D.

A minor feature of the design consists in projecting the edges of the plates A and B beyond the outer surfaces of the bosses C C' and D, as plainly shown in the drawings.

I claim—

The design for a bicycle-crown herein shown and described.

HUGH DANIEL McCARTY.
